UNITED STATES PATENT OFFICE.

JULIUS L. CABELINSKY, OF BOSTON, MASSACHUSETTS.

GARMENT.

1,246,871.

Specification of Letters Patent. Patented Nov. 20, 1917.

Application filed September 21, 1916. Serial No. 121,355.

To all whom it may concern:

Be it known that I, JULIUS L. CABELINSKY, a citizen of the United States, residing at Boston, in the county of Suffolk and State 5 of Massachusetts, have invented an Improvement in Garments, of which the following is a specification.

It is customary to provide, in connection with rain coats of thin material, adapted to 10 be folded into a small space, a bag or sack in which the garment may be placed, when folded, to make a small bundle. As this bag frequently becomes lost or misplaced, or is liable not to be at hand when wanted, this 15 method of providing a case for the garment is open to objection.

The object of my invention is to provide, in connection with an ordinary rain coat, or like garment, a convenient means for receiving 20 the garment, which is incorporated in, or practically made a part of the garment.

I accomplish this object by the means shown in the accompanying drawing, in which;—

25 Figure 1 is a view of the inner side of an ordinary rain coat provided with means embodying my invention.

Fig. 2 is a sectional view on the line 2—2 of Fig. 1.

30 Figs. 3 to 7, inclusive, are views showing the different steps in the folding of the coat, preparatory to placing it in the holding sack.

Figs. 8 and 9 are views of opposite sides 35 of the package, after the garment has been placed in the sack.

In the drawing, *a* indicates the body of an ordinary rain coat of thin, waterproof material, which is adapted to be readily folded.

40 The usual transversely-extending side-pocket-opening *a'* is formed through the garment approximately midway of its length, and a pocket-section *b* is attached to the garment about the upper edge of the 45 opening *a'* and depends at the inner side of the garment. The usual flap *c*, for the pocket-opening, is preferably provided.

According to my invention, I provide a 50 sack *d*, one side-portion of which is attached at its top edge to the garment about the under side of the pocket-opening *a'*, so that its opposite top-edge-portion hangs loosely against the inner side of the garment, the side and bottom edge-portions of the pocket-section *b* being attached to the side of the

sack *d*, which is attached to the garment, so that a pocket is formed therebetween, one side of the sack thus forming one side of the pocket. In this connection, it may be noted that it is not of vital importance 60 whether the sack *d*, or the pocket be formed of continuous material, but it is advantageous to have the same piece of material serve both as the side of the pocket and of the sack. The unattached portion of the 65 mouth of the sack *d* is provided with an elastic drawing band *e*, which is adapted to contract the mouth of the sack.

When the coat is in use, the sack *d* merely hangs between the pocket and the inner side 70 of the coat, as best illustrated in Fig. 2, and when the coat is to be folded and placed therein, it is first folded so that the folds are of the same width as the mouth of the sack, as best shown in Fig. 3, and then it is 75 doubled at the pocket-opening, which is approximately midway of its length, so that the folded garment lies at one side of the sack, and it is not overlapped thereby, as indicated in Figs. 4 and 5. The garment as 80 thus folded is then again folded transversely, until the length of the fold is substantially the same as the depth of the bag, as shown in Figs. 6 and 7, and then it is inserted in the bag, or the latter is drawn thereover, the 85 mouth of the sack being permitted to contract about it, as shown in Figs. 8 and 9, so that a compact bundle is formed.

The above-described construction increases the cost of manufacture but slightly, and a 90 case is thus provided for the garment which is always at hand.

I claim:—

1. A garment of the character described, having a pocket-opening located in the middle portion of its length, two sacks arranged side by side and having a common intermediate side-portion, the mouth of one of said sacks being connected to the garment about said opening to form a pocket, and arranged 95 at the inner side of the garment, and the other sack being arranged between the pocket and the garment and having the portion of its mouth opposite the pocket provided with an elastic band and adapted to be opened to 100 receive the folded garment therein.

2. A garment of the character described having a pocket opening accessible from the outside of the garment, a pocket arranged on the inner side of the garment leading 110

from said opening, and a section of material secured to the pocket outwardly beyond the same and forming with one wall of the pocket a sack, the relatively upper edge of 5 the section being free of connection with the pocket to provide an opening leading to the sack from the inner side of the garment,

whereby the garment is adapted to be folded and inserted into said sack.

In testimony whereof, I have signed my 10 name to this specification.

JULIUS L. CABELINSKY.
